St. Louis, Mo. 63110

Filed Oct. 23, 1967, Ser. No. 9,110

Term of patent 14 years

(Cl. D54—13)

FIG. 1

FIG. 2

FIG. 3

FIG. 4

FIG. 5

FIG. 1 is a top view of a hog ring plier tool embodying my new design.

FIG. 2 is a side view of the tool when closed; the opposite side is a duplicate of FIG. 2.

FIG. 3 is a bottom view of the tool.

FIG. 4 is a side view of the tool when fully open to receive a hog ring.

FIG. 5 is an end view and section on line 5—5 of FIG. 4.

The broken lines in the figures indicate a hog ring before being bent as shown in FIGS. 4 and 5, and after being bent as shown in FIG. 2, these showings being for the purpose of illustration only.

I claim:

The ornamental design for a hog ring plier tool, substantially as shown and described.
